PETER W. KRAUSS, OF SCRANTON, PENNSYLVANIA, ASSIGNOR TO TECHNICAL SUPPLY CO., OF SCRANTON, PENNSYLVANIA, A CORPORATION OF NEW JERSEY.

CLAMPING ATTACHMENT FOR T-SQUARES.

1,121,512.

Specification of Letters Patent. Patented Dec. 15, 1914.

Application filed June 3, 1914. Serial No. 842,736.

To all whom it may concern:

Be it known that I, PETER W. KRAUSS, a citizen of the United States, residing at Scranton, in the county of Lackawanna and State of Pennsylvania, have invented new and useful Improvements in Clamping Attachments for T-Squares, of which the following is a specification.

This invention relates to an improved 10 clamping attachment for T-squares, proposing a device which will hold a T-square against displacement from any desired position upon a drawing board but at the same time will permit the T-square to be readily 15 and quickly adjusted from one position to another.

The objects of the invention are to provide a device for the purpose stated, which may be quickly and conveniently applied to 20 any ordinary T-square and entails no modification of the construction of the T-square or of the drawing board; which reliably and certainly performs the function for which it is designed; which permits the ready removal 25 of the T-square from the drawing board and the ready assemblage of the T-square upon the drawing board; and which is readily adjustable along the blade of the T-square and permits of the ready adjustment 30 of the T-square along the drawing board.

Further objects of the invention are to provide an attachment for the purpose stated which shall be of an exceedingly simple structural nature; inexpensive to manufacture; readily manipulatable and comparatively small and inconspicuous.

An embodiment of the invention is illustrated in the accompanying drawings, 40 wherein:—

Figure 1 is a plan view showing the attachment in its application to an ordinary T-square and showing the latter in position upon a drawing board; Fig. 2 is an elevation looking at the inner side of the attachment; Fig. 3 is a perspective view of the attachment; Fig. 4 is a cross-sectional view of the attachment.

Similar characters of reference designate 50 corresponding parts throughout the several views.

The attachment is designed to be clamped upon the blade of the T-square and to take a bearing against the adjacent face of the 55 drawing board. For these purposes the at-

tachment includes essentially a clamping plate 1 and a bearing plate 2. The plates 1 and 2 are disposed at right angles to one another, together having an L-shaped cross-section, and are preferably integrally joined, the plate 1 projecting from an edge of the plate 2. In the drawings, the plate 1 is shown as horizontally disposed and as projecting from the upper edge of the plate 2 which of course occupies a vertical plane. 60 The plate 2 is formed immediately under the plate 1 with a slot 3 through which the blade of the T-square upon which the attachment is fitted projects, the length and width of this slot being selected to enable 65 the attachment to be used on the larger as well as the smaller T-squares. Adjacent the lower edge of the slot 3 the plate 2 is provided with lugs or brackets 4 which are located immediately under the plate 1 in 70 spaced parallel relation thereto and complement the plate 1 to provide a clamp. The plate 1 is provided with a clamping screw 5 which is preferably centrally located and at its lower end engages a leaf spring 6 75 which at one end is secured to an adjoining face of the plate 1 and adjacent the end face of said plate. The provision of the spring 6 is preferred for the reasons that said spring prevents the blade of the T-square 80 from being marred by the end of the screw, and furthermore, takes a relatively wide, uniform and strong frictional bearing against said blade whereby to prevent accidental displacement of the attachment 85 lengthwise of the blade but to permit the ready adjustment of the attachment to any position on the plate, whenever the occasion may require, and without the manipulation of the screw 5.

The plate 2 is provided with a spring 7 which is preferably, as shown, secured at a point central thereof to said plate as at 8 and has the portions at either side of its attached central portion 8 formed to provide 90 100 spring bows which project beyond the lugs 2 and engage the adjacent face of the drawing board A.

The device is fitted in position upon the blade of the T-square in the obvious manner 105 and is moved to a position against the adjoining face of the drawing board and while the device is being held with pressure to said face the screw 5 is turned downwardly so as to cause the spring 6 to engage the 110

blade of the T-square with strong frictional pressure, sufficient to overcome or resist the tension of the spring 7. Should it be necessary to move the T-square along the drawing board, this is done in the usual manner by sliding the T-square to the position desired against the resistance opposed by the spring 7, in consequence of its frictional engagement with the edge of the drawing board. Should it be desired to change the position of the attachment upon the blade of the T-square, this is done by moving the attachment lengthwise of the T-square against the resistance opposed by the spring 6 in consequence of its frictional engagement with the blade of the T-square. The T-square may be readily removed from the drawing board and readily replaced, whenever the occasion may require, without any manipulation of the attachment. The blade of the T-square has a measure of springiness or resiliency, as is well known. A convenient way of removing the T-square consists of pressing the plate 2 toward the adjoining edge of the board A so as to disengage the head of the T-square from the opposite edge of said board, at which time the head of the T-square is sprung upwardly and the square is thus freed from its engagement with the board. Assuming that the proper adjustment of the attachment has been made, in order to apply the T-square to the board the operations described are reversed; that is to say, the plate 2 is pressed toward the adjoining edge of the board A and the head of the T-square is depressed into co-planar relation with the board, at which time the pressure on the plate 2 is released and the spring 7 exercises its clamping function.

The length of the slot 3 will, in most cases, be greater than the width of the blades of the T-squares ordinarily used. By virtue of this fact, the clamp may be used with swivel-head T-squares, which have their blades adjusted to extend obliquely of the drawing board, as well as with the ordinary solid-head T-squares, such as shown in the drawing.

From the foregoing description it will be apparent that the device includes essentially a means for clamping it upon the T-square and a means for clamping the T-square to the drawing board, and that the said means are both preferably so constructed that the adjustment of the device itself along the blade of the T-square and the adjustment of the T-square along the drawing board entails no manipulation of any parts.

Having fully described my invention, I claim:

1. A clamping attachment for T-squares

comprising a clamping plate, a bearing plate carrying the clamping plate and having a slot immediately under the clamping plate through which the blade of the T-square may be inserted, a pair of lugs carried by the bearing plate and projecting under the clamping plate in parallel relation thereto adjacent the lower edge of the slot, a leaf spring carried by the clamping plate to engage the blade of the T-square, a screw for causing said spring to engage said blade and resilient means carried by the bearing plate to engage the edge of the board upon which the T-square is positioned.

2. A clamping attachment for T-squares comprising a clamping plate, a bearing plate carrying the clamping plate and having a slot immediately under the clamping plate through which the blade of the T-square may be inserted, a pair of lugs carried by the bearing plate and projecting under the clamping plate in parallel relation thereto adjacent the lower edge of the slot, a leaf spring carried by the clamping plate to engage the blade of the T-square, a screw for causing said spring to engage said blade and a leaf spring carried by the bearing plate to engage the edge of the board upon which the T-square is positioned.

3. A clamping attachment for T-squares comprising a clamping plate, a bearing plate, the clamping plate and the bearing plate together having an L-shaped cross section, the bearing plate having a slot immediately under the clamping plate through which the blade of the T-square may be inserted, clamping means carried by the clamping plate to frictionally engage said blade, and resilient means carried by the bearing plate to engage the board upon which the T-square is mounted.

4. A clamping attachment for T-squares comprising a clamping plate, a bearing plate, the clamping plate and the bearing plate together having an L-shaped cross section, the bearing plate having a slot immediately under the clamping plate through which the blade of the T-square may be inserted, clamping means carried by the clamping plate to frictionally engage said blade, and a leaf spring carried by the bearing plate to engage the board upon which the T-square is mounted.

In testimony whereof I have hereunto set my hand in presence of two subscribing witnesses.

PETER W. KRAUSS.
